SANDING MACHINE

Lewis Samuel Farner, New Kensington, Pa.

Application July 17, 1944, Serial No. 545,231

5 Claims. (Cl. 51—166)

My invention relates, generally, to abrading machines, and more particularly to sanding machines for shaping and cleaning pitted and burnt welding tips such as are used in spot welding.

The primary object of my invention is to provide a simply constructed, inexpensive machine for shaping and cleaning such tips quickly and easily and which is especially designed for power drive of shaping and cleaning implements and for maximum flexibility as regards adjustment into different angular positions of the shaping and cleaning implements while the same are being driven.

Other and subordinate objects are also comprehended by my invention, all of which, together with the precise nature of my improvements, will be readily understood when the succeeding description and claims are read with reference to the drawings accompanying and forming part of this specification.

In said drawings:

Figure 1 is a view in front elevation of my improved sanding machine, in its preferred embodiment.

Figure 2 is a view in end elevation.

Figure 3 is a view in plan.

Figure 4 is a view in plan of one of the sanding implements.

Figure 5 is a view in transverse section taken on the line 5—5 of Figure 3 and drawn to an enlarged scale.

Figure 6 is a similar view taken on the line 6—6 of Figure 3.

Referring to the drawings by numerals, my improved sanding machine, in the embodiment illustrated, comprises a base bar 1 provided with end apertures 2 for securing the same, as by screws, not shown, in upright position to a fixed support of any suitable type.

A U-shaped, right-angled bracket 3, of bar-like form, is pivotally mounted intermediate its ends, and centered on the bar 1, by a shouldered bolt 4, so that said bracket is swingable about an horizontal axis.

A motor 5 is pivotally mounted on the bracket 3, with its armature shaft 6 disposed upright, and to swing with said bracket 3 and also on the same about a vertical axis. The pivotal mounting for the motor 5 has the form of a pair of bearing lugs 7 extending radially from the motor casing and fitting in between the ends of the bracket 3, with bolts 8 extending through said lugs and said ends of the bracket. An arcuate slot 9 in the bracket 3, through which a

pin 10 on the bar 1 extends, limits swinging of the bracket 3 and motor 5 relative to said bar 1.

A Y-shaped yoke frame 10 extends laterally from the motor 5 with rear ends 11 straddling the motor 5 and journaled on the opposite ends of the armature shaft 6 so that said frame 10 is swingable horizontally about said shaft as an axis.

Adjacent the front end of the yoke frame 10 is 10 a pair of upper and lower pulleys 11, 12 fast upon the ends of an upright shaft 13 journaled in said frame in a manner presently described. A belt 14 extends from a pulley 15 fast on the upper end of the armature shaft 6 and is trained around the upper pulley 11, whereby said motor 5 is operatively connected to said pair of pulleys 11, 12. The shaft 13 is rotatably mounted in an upright bushing 16 suitably fixed in the yoke frame 10.

20 An extension arm 17 projects horizontally from the front end of the yoke frame 10 and is swingably mounted on said end by a pair of rigid links 18 extending from its rear end with a spacer 19 therebetween, said links straddling said front 25 end of the yoke frame 10 and being journaled on the described bushing 16 and fixed to said arm by screws 20.

A bar-like bracket 22 is mounted in upright 30 position on an upturned front end tongue 23 on the arm 17, and by means of a bolt 24 and wing nut 25, the arrangement being such that said bracket 22 may be tilted on the tongue 23 about an horizontal axis into different set positions.

35 A guide rod 26 extends through right-angled ends 21 of said bracket 22 and beyond one end 21 of the bracket to form a manipulating hand grip 27, the purpose of which will presently be seen.

40 A flat implement-carrying arm 28 is slidably mounted at its rear end on the guide rod 26 by a bushing 29 fixed in said end of said arm and confined between the ends 21 of said bracket 22. The arm 28 fits in the bracket 22 so that 45 it is prevented from turning on the guide rod 26 and is provided, intermediate its ends, with a laterally extending handle bar 30 for sliding the same.

50 A pair of opposed, axially aligned, disc-like shaping and cleaning implements 31 is provided at each side edge of the implement-carrying arm 28 at the outer end thereof, this pair being aligned transversely of said arm. The implements 31 each comprises a circular body 32 having on the outer side face thereof an edge flange 33 of

right-angled form in cross section and forming an internal, annular, edge groove 34 around the outer face of the body 32. The bodies 32 of each pair of implements 31 are fixed upon an axial stud 35 journaled in the arm 28, the arrangement being such that the bodies of each pair are imposed flat against opposite side faces of the arm 28. The opposed sides of the bodies 32 of each pair of implements 31 are grooved around their edges, as at 35, so that each pair of bodies 32 forms therebetween a pulley. A belt 36 is trained around the bodies 32 and around the pulley 12, whereby said pairs of implements 31 are driven by the motor 5, as will be clear. A rubber, or like, material disc 37 is fitted in each groove 34, as a resilient backing for an abrasive disc 38 also fitting in each groove 34 with the following exception. Each disc 37 is provided with diametrically opposite flattened side edges 39 for engagement with pairs of transverse pins 40 extending through the flange 33 and groove 34 of the body of the implement, and whereby the abrasive disc 38 is keyed to the body 32 for rotation thereby. The discs 38 may be provided with outer abrasive faces of different types, for instance, coarse or fine, for use in different phases of the shaping and cleaning operation.

The motor 5 is designed to be controlled by a suitable foot pedal, not shown, so that the hands of an operator are left free for manipulation of the described implements over and around the tips one of which is represented in dotted lines at 41.

As will now be seen, the entire device, with the exception of the bar 1, may be swung vertically on the bolt 4, the yoke frame 10, with parts carried thereby, may be swung horizontally about the motor 5, the extension arm 17, and the parts thereon, may be swung horizontally on the yoke frame 10 independently, the bracket 22 may be adjusted at different angles to the arm 17 to correspondingly adjust the implements 31, and the implement-carrying arm 28 may be slid laterally of the bracket 22 independently, all facilitating the use of the described implements 31 selectively on the tips so that the shaping and cleaning of the tips may be quickly and conveniently accomplished.

The foregoing will, it is believed, suffice to impart a clear understanding of my invention without further explanation.

Manifestly, the invention, as described, is susceptible of modification without departing from the inventive concept, and right is herein reserved to such modifications as fall within the scope of the appended claims.

What I claim is:

1. In a machine of the class described, a motor adapted to be mounted on a base and having an armature shaft, means to mount said motor on said base with said shaft in upright position, a yoke frame having a rear end straddling said motor and swingably mounted on opposite ends of said shaft, opposed pairs of disc-like abrading implements axially aligned in each pair, means to mount said pairs of elements on the outer end of said yoke frame for rotation in unison and adjustment bodily in unison into different angular positions independently of swinging of said frame, and driving connections between said shaft and said implements.

2. In a machine of the class described, a motor adapted to be mounted on a base and having an armature shaft, means to mount said motor on said base with said shaft in upright position,

a yoke frame having a rear end straddling said motor and swingably mounted on opposite ends of said shaft, opposed pairs of disc-like abrading implements axially aligned in each pair, means to mount said pairs of elements on the outer end of said yoke frame for rotation in unison and adjustment bodily in unison into different angular positions independently of swing of said frame, and driving connections between said shaft and said implements, said means comprising an arm swingably mounted on the front end of said yoke frame, an implement-carrying arm, and means to mount said implement-carrying arm on said swingable arm for sliding adjustment laterally of said swingable arm and for tilting adjustment laterally into different positions.

3. In a machine of the class described, a motor adapted to be mounted on a base and having an armature shaft, means to mount said motor on said base with said shaft in upright position, a yoke frame having a rear end straddling said motor and swingably mounted on opposite ends of said shaft, opposed pairs of disc-like abrading implements axially aligned in each pair, means to mount said pairs of elements on the outer end of said yoke frame for rotation in unison and adjustment bodily in unison into different angular positions independently of swinging of said frame, and driving connections between said shaft and said implements, said connections comprising a driving belt, said pairs of implements forming therebetween pulleys around which said belt is trained.

4. In a machine of the class described, a motor adapted to be mounted on a base and having an armature shaft, means to mount said motor on said base with said shaft in upright position, a yoke frame having a rear end straddling said motor and swingably mounted on opposite ends of said shaft, opposed pairs of disc-like abrading implements axially aligned in each pair, means to mount said pairs of elements on the outer end of said yoke frame for rotation in unison and adjustment bodily in unison into different angular positions independently of swinging of said frame, and driving connections between said shaft and said implements, said implements comprising respectively a disc-like body having an internally grooved edge flange, a backing disc of cushioning material fitted in said groove, and an abrasive disc fitted in said groove on said backing disc.

5. In a machine of the class described, a motor adapted to be mounted on a base and having an armature shaft, means to mount said motor on said base with said shaft in upright position, a yoke frame having a rear end straddling said motor and swingably mounted on opposite ends of said shaft, opposed pairs of disc-like abrading implements axially aligned in each pair, means to mount said pairs of elements on the outer end of said yoke frame for rotation in unison and adjustment bodily in unison into different angular positions independently of swinging of said frame, and driving connections between said shaft and said implements, said implements comprising respectively a disc-like body having an internally grooved edge flange, a backing disc of cushioning material fitted in said groove, and an abrasive disc fitted in said groove on said backing disc, said abrasive disc having flattened edge portions, and pins extending through said flange and groove alongside said flattened portions to key the abrasive disc to said body.
